UNITED STATES PATENT OFFICE.

EARL V. COULSTON, OF ROCK ISLAND, ILLINOIS.

HEATING SYSTEM.

1,308,335.

Specification of Letters Patent.

Patented July 1, 1919.

Application filed March 19, 1917. Serial No. 155,873.

To all whom it may concern:

Be it known that I, EARL V. COULSTON, a citizen of the United States, resident of Rock Island, county of Rock Island, and State of Illinois, have invented new and useful Improvements in Heating Systems, of which the following is a specification, the principle of the invention being herein explained and the best mode in which I have 10 contemplated applying that principle, so as to distinguish it from other inventions.

My invention relates to heating systems and particularly to that class of such devices adapted to dispense with the necessity of providing pipes in the basement for conveying warm air to different parts of the house. Furthermore, said invention relates particularly to such devices as will permit both the warm air for heating the house and the 20 supply of colder air for keeping the circulation in operation to pass through a single register.

The annexed drawings and the following description set forth in detail certain means embodying my invention, the disclosed means, however, constituting but one of various mechanical forms in which the principle of the invention may be employed.

In said annexed drawings:—

30 Figure 1 represents a central vertical section of my improved heating system; Figs. 2 and 3 represent transverse sectional views taken in the planes represented by the lines II—II and III—III, respectively, Fig. 1.

35 My improved heating system comprises as its foundation a warm air furnace or heater of general or common construction to which is attached, in the manner hereinafter fully described, the new and improved features 40 constituting my improvement.

In the annexed drawings, a warm air furnace or heater of general or common construction is shown at 1, provided with a round casing 2, with its bottom portion cut away and having a lower casing ring 3 supported by four cast iron legs 4. A main circular base for the heater is shown at 5. Said construction will provide a hot air passage 19 between the walls of the casing 2 and the furnace 1, as is readily understood. 45 For the purposes of my new and improved attachments, there is provided a rectangular auxiliary base 6 attached at 7, 7, to the circular base 5 and surrounding the latter. Said construction will provide a hot air passage 19 between the walls of the casing 2 and the furnace 1, as is readily understood.

50 For the purposes of my new and improved attachments, there is provided a rectangular auxiliary base 6 attached at 7, 7, to the circular base 5 and surrounding the latter. Said construction will provide a hot air passage 19 between the walls of the casing 2 and the furnace 1, as is readily understood. For the purposes of my new and improved attachments, there is provided a rectangular auxiliary base 6 attached at 7, 7, to the circular base 5 and surrounding the latter. Said construction will provide a hot air passage 19 between the walls of the casing 2 and the furnace 1, as is readily understood.

base 6 in sections, is an auxiliary rectangular casing 8, a flange 6' being provided upon the base 6 for this purpose, as shown. When the sections forming the walls 9 of the auxiliary casing are in place, a rectangular top 10 in two sections 11 and 12 is placed upon the top of these walls and around the outer edge of the round hot air collar 1' in the dome of the casing 2, said sections 11 and 12 being provided with rectangular 60 openings 11' and 12', respectively. A round pipe 13 fits over the hot air collar 1' and an additional round pipe 14 with a top flange 14' fits over and telescopes with pipe 13. Rectangular pipes 15 are provided, having 70 bottom flanges 15' supported upon the top 10 so as to register with the openings 11' and 12'. Telescoping with the pipes 15 and fitting upon the outside of the same are rectangular pipes 16 with upper flanges 16'. 75 Rigidly suspended in the floor above the furnace is an auxiliary box 17 in connection with the surface register 18, said box 17 being provided with a circular opening 17' upon the edge of which hangs the pipe 14 80 by its flange 14', and two rectangular openings 17' upon the edges of which hang the pipes 16 by their flanges 16'. Transverse division walls 17' separate the hot air section 17' of box 17 from the cold air sections 85 17' thereof. This box 17 is of sufficient size to permit the use of a register 18 sufficiently large enough to possess in its open spaces between the usual lattice-work thereof, a free air passing area equal to or greater than the 90 combined areas of the cold and warm air pipes 15 and 13. This insures a condition wherein all the heated air that ascends through pipe 14 will have room enough to spread out and pass through the open spaces 95 of a larger area of register and also wherein an equal amount of cold air will pass down and through pipes 16 and 15 to space 20 between casings 2 and 8. By reason of the casing 2 being cut away at the bottom, 100 as hereinbefore mentioned, there is provided the opening 21 between the passages 19 and 20.

It will be apparent from the foregoing description that the air in the passage 19 105 will be heated and will ascend up around the heater and through the round pipe 13, telescoping pipe 14, circular opening 17' in the auxiliary box 17 and through the register 18 to the apartments to be heated. Also, 110

the cold air in the apartments will fall through the ends of the register 18 and openings 17² of the box 17, through the rectangular pipes 16 and 15, passage 20 and then through the opening 21, from which point it gradually becomes heated and ascends around the heater.

The advantages attaching to my improved heating system hereinbefore fully shown 10 and described, are as follows:

(1) By providing an auxiliary box in connection with the surface register, the area of the latter in its free spaces between the usual lattice-work thereof is equal to or greater 15 than the combined areas of the cold and warm air pipes and will pass their total contents, a condition that would not exist if the hot air and cold air pipes were connected directly to the register, without any box 20 or expansion chamber beneath, because the lattice-work of the usual register closes up about one-half of its area and therefore would pass only about one-half the contents of a pipe directly connected thereto.

(2) By providing the auxiliary casing of rectangular cross-section, I thereby secure large spaces at each corner of this casing where the cold air can pass down rapidly with minimum friction and in large volumes 30 so as to keep up a more positive and complete circulation.

(3) By means of the flanges supporting upper sections of pipes from the box 17 above and other flanges supporting the lower sections of said pipes from the casing below, the said pipes are flexible and can be drawn to various lengths making the plant adaptable to basements of varying heights without any cutting or changing of material.

(4) My construction is simple and easily assembled and requires only a man of ordinary ability and a short time to set up the heater in any house, being designed in fact 45 for the advantage of dwellers in rural districts who often must do their own erecting.

Having fully described my invention, what I claim and desire to secure by Letters Patent is:—

50 1. In heating systems, a heating element containing a hot air flue; a surrounding casing containing a cold air flue communicating with said hot air flue; a register; a box below such register and communicating 55 with the apertures thereof; and telescoping pipes joining said hot air flue and said box, the upper pipe being dependently supported from the box and the lower pipe being supported by the element forming the hot 60 air flue.

2. In a device for heating dwellings in combination, a furnace, a casing about said furnace terminating in a hot air collar, a hot air pipe fitting said collar and forming an 65 extension thereof, a register, a box having

flanged division walls arranged below said register, a flanged pipe depending from the flanges of said division walls and connecting adjustably with said hot air pipe, and means surrounding said casing for conducting cold 70 air downward and discharging it into the bottom of said casing, whereby a circulation of air through a house may be effected.

3. In a device for heating dwellings in combination, a furnace, a round casing about 75 said furnace, terminating in a hot air collar, a hot air pipe fitting said collar and forming an extension thereof, a surface register above said furnace, a box having flanged division walls depending from said 80 register, a flanged pipe depending from the flanges of said division walls and connecting adjustably with said hot air pipe, cold air boxes upon the remote sides of said depending walls, cold air pipes supported by said 85 cold air boxes, flanged lower pipes adjustably connected to said cold air pipes, a rectangular cold air casing surrounding said round casing to form a cold air passage, and a top fitting said cold air casing, said top 90 provided with openings through which pass the hot air collar and said lower cold air pipes and upon which top said cold air pipes are supported by their said flanges.

4. In a device for heating dwellings, in 95 combination, a floor grating, a box disposed therebeneath, flanged walls depending in said box, said walls providing a central air space, a flanged adjustable hot air pipe depending from said flanged walls, said 100 flanged walls providing also side cold air spaces, flanged cold air pipes supported in said cold air spaces by said wall flanges, said cold air pipes spaced from said hot air pipe, a furnace, upward hot air and downward 105 cold air conduits provided for said furnace, and pipes supported on said conduits, and connecting said conduits telescopically with said depending hot and cold air pipes, whereby after the furnace and conduits are 110 set up, the pipes connected therewith may be telescopically adjusted over said furnace according to the distances between the furnace and the box.

5. A hot air heating device for dwellings, 115 consisting of a furnace provided with a hot air conduit around and extending above it and a cold air conduit around that and extending above the furnace, pipes uprising 120 from said conduits, and a grating having means for supporting in dependent relation to said grating hot and cold air pipes, the dependent pipes and the uprising pipes adapted to be arranged to meet in telescopically adjustable relation.

6. A hot air heating device for dwellings consisting of a furnace provided with a hot air conduit around and above it, a cold air conduit around that and above the furnace, a floor register, a box below the register, 125

partitions in said box, hot and cold air pipes depending from said box and arranged to register telescopically with the furnace conduits, the partitions being arranged to 5 divide the box and register into hot and cold air divisions, the unobstructed areas of said divisions of the register being approxi-

mately proportionate to the sectional areas of the corresponding hot and cold air pipes, whereby free circulation is maintained at all 10 times.

Signed by me, this 7th day of March, 1917.

EARL V. COULSTON.
